UNITED STATES PATENT OFFICE.

JOSIAH SPARKS, OF UNIVERSITY PLACE, NEBRASKA.

AIRSHIP.

1,010,324.

Specification of Letters Patent. Patented Nov. 28, 1911.

Application filed May 6, 1911. Serial No. 625,446.

To all whom it may concern:

Be it known that I, JOSIAH SPARKS, a citizen of the United States, residing at University Place, in the county of Lancaster and State of Nebraska, have invented certain new and useful Improvements in Airships, of which the following is a specification, reference being had to the accompanying drawings.

10 My invention relates to new and useful improvements in the art of aerial navigation and more particularly to the construction of an aerial vessel or air ship which will be practically operative, and my object is to 15 provide a ship of this character which, although not buoyant, will be adapted to fly through the air.

A further object is to provide the device with such strength as to withstand the extremely heavy pressure which the same will 20 encounter in its course and to provide for the dirigibility of the same, and by the latter, I mean the ability to direct the course of the machine upwardly, downwardly and 25 in all directions.

A still further object resides in providing the device with top, front and rear propellers and to provide the machine with twin engines for operation of the propellers.

30 A further object of the invention resides in providing means whereby the engines may be operated independently or in conjunction with one another for the operation of the propellers.

35 Still another object of the invention resides in providing pivotally mounted wings and parachutes on the device to aid the same in safely descending.

With these and other objects in view, my 40 invention consists in the novel features of construction, combination and arrangement of parts as will be hereinafter referred to and more particularly pointed out in the specification and claims.

45 In the accompanying drawings forming a part of this application, Figure 1 is a front elevation of the machine. Fig. 2 is a top plan view thereof with the upper plane removed. Fig. 3 is a fragmentary longitudinal section as seen on line 3—3, Fig. 2. Fig. 4 is a detail perspective of one end of the machine showing the parachute and wing thereon, and, Fig. 5 is a detail perspective view showing the operating lever for the 55 wings.

In carrying out my invention, I shall re-

fer to the drawings in which similar reference characters designate corresponding parts throughout the several views and in which 1 and 2 indicate, respectively, upper 60 and lower planes which may be made of any desired material which is light and strong, said planes being spaced apart by means of the vertical side and end bars 3. These planes are braced by means of the usual 65 brace wires 4 to the vertical bars, said lower plane being somewhat shorter than the upper plane, and said lower plane has mounted thereon, the axles 5, upon the ends of which are carried the wheels 6, whereby the device 70 may be readily moved on the ground.

Mounted on the longitudinal center of the machine and extending through the upper and lower planes adjacent their ends, are the vertical shafts 7 and 8, said shafts being 75 rotatably mounted in the bearings 9 on said planes, and the upper ends of said shafts which extend beyond the upper plane 1, have mounted thereon, the propellers 10 and 11, respectively. Extending transversely of the 80 machine and rotatably mounted in the bearings 12 on the end vertical bars of the same, are the horizontal shafts 13 and 14, said shafts extending a short distance beyond the front and rear of the planes, and each has 85 mounted on the ends thereof, the propellers 15 and 16, respectively.

Mounted on the lower plane 2 on opposite sides of the transverse center thereof, are the engines 17 and 18, respectively, which 90 drive, respectively, through the medium of the belts 19 and 20, the transverse shafts 21 and 22. These transverse shafts are rotatably mounted in bearings 23, on the bracing bars of the machine the same being positioned a short distance above the lower plane 2, and mounted on each of said shafts 21 and 22, is a pair of drums or pulleys 24 and 25, said pulleys or drums being positioned adjacent the ends of their respective 95 shafts. Extending over the pulleys or drums 24 and 25, respectively, are the belts 26 and 27 which also extend over the similar drums or pulleys 28 and 29, on each of the transverse propeller shafts 13 and 14, and the drums 24 and 25 are loosely mounted on the shafts 21 and 22, so as not to normally rotate said shafts when the same are rotating, but a clutch 29' is provided for each of said drums on said shafts 21 and 22 which 100 are operable by means of a lever 30, whereby said drums may be moved into operative 105

connection with the shafts to rotate therewith.

The shafts 21 and 22 are also provided, respectively, with additional drums 31 and 32, over which extend the endless belts 33 and 34, said belts also extending over the drums 35 and 36, respectively, mounted on the vertical propeller shafts 7 and 8, and the drums 31 and 32 are also loosely mounted 10 on their respective shafts, but in order to allow said drums to rotate with the same, the clutches 37 are provided, which are operable by means of a lever 38, whereby said drums and correspondingly the shafts 7 and 8 may be rotated with the shafts 21 and 22, when desired. As before stated, the shafts 21 and 22 are driven, respectively, by the engines 17 and 18 through the medium of the belts 19 and 20, but I have also provided 15 for the conjunctive operation of said shafts from either one engine or the other, and to this extent, I provide said shafts with additional clutch mechanisms 39 and 40 which have connection with one another through 20 the medium of a chain or the like 41. These clutches may be thrown into and out of effective position by means of the levers 42 and 43, respectively, and thus, it will be seen that the sets of propellers on one side 25 of the machine may be operated without the operation of the other set, or all of the propellers may be operated through the operation of one of the engines, whereby it will be seen that provision has been made 30 for any possibility of accidents to the various propellers, or to one engine or the other.

Mounted about centrally of the lower plane 2, is a seat 44 adapted to carry one or more passengers, as desired, and the 40 levers which have heretofore been described, are, of course, all positioned in convenient points adjacent the seat. It will also be understood that the controlling devices for the engines 17 and 18 are positioned adjacent the seat so that the speed of said 45 engines may be readily regulated by the operator, and thus, one engine may be caused to operate with more or less speed than the other, if desired, the purpose of which will 50 be hereinafter described.

Extending longitudinally the full length of the upper plane and beyond the ends thereof, is a shaft 44' rotatably mounted in the bearings 44^a, to the ends of which shaft, 55 are pivotally connected the wings 45 and 46. A lever 47, having a yoke 47' at the upper end thereof pivotally attached to the shaft about centrally, is connected to the wings by means of the wires 45' and 46', 60 said wires being engaged with the lever above and below the pivotal point, respectively, whereby when said lever is moved in one direction, both wings will be raised, and when moved in the other direction, the 65 same will be lowered. However, when the

lever is moved in a direction at right angles to the direction which disposes the wings upwardly and downwardly, said shaft 44' will be rotated in its bearings, thereby disposing said wings at angles to the planes 70 of the front and rear of the machine, and it will be seen that when disposed at these various angles, said wings will aid in the various movements of the machine. Also carried by the machine on the vertical end 75 bars thereof, are the parachutes or the like 48 and 49 which are made of any desired material, preferably canvas, and are disposed normally in a closed position. These parachutes may be of any desired shape 80 and size and are formed on collapsible frames 50 and 51, respectively, which frames have connection, in any desired manner, to an additional lever 52, whereby the same may be opened and closed at will. Both the 85 levers 47 and 52 are also disposed in convenient places adjacent the seat 44, whereby the same may be readily grasped by the operator for the purpose of raising and lowering the wings and opening and closing 90 the parachutes.

In operation, the engines are first started with all the clutches being thrown out of their effective positions, and when it is desired to ascend at an angle upwardly, the 95 clutches 29' and 37 are thrown into their effective positions by means of the levers 30 and 38, respectively, whereupon the vertical shafts 7 and 8 and the horizontal shafts 13 and 14 will be rotated to, correspondingly, 100 rotate the propeller blades thereon. The rotation of the propeller blades on the horizontal shafts will cause the machine to be driven forwardly, and the simultaneous rotation of the blades on the vertical shafts 105 will cause the machine to ascend, so that the same will rise upwardly and travel forwardly at the same time. After reaching a considerable height in the air, the operator may release the clutch 37 to stop the rotation of the vertical propeller shafts and increase the speed of the engine so as to propel the horizontal shafts at a greater rate of speed and the machine may soar at this height, and when it is desired to descend, 110 the speed of the front and rear propellers may be decreased and the clutches 37 again thrown into effective position so as to rotate the top propellers at a slow rate of speed and thus, the machine will descend at an 115 120 angle. In the lowering of the machine, the parachutes may be thrown into their open positions so as to catch the breeze and allow the machine to be lowered gently, and in both the raising and lowering of the machine, the wings 45 and 46 may also be used 125 to aid in guiding the same.

As just stated, the moving of both the clutches 29' and 37 into their effective positions, causes the machine to ascend at an 130

angle, but it will be readily understood that the machine may also ascend in a substantially vertical plane by merely throwing the clutches 37 into their effective positions, which will rotate the top propellers, and when the machine has reached the proper or desired height, the clutches 29 may be thrown into their effective positions to rotate the front and rear propellers, whereby the machine may be driven forwardly at the same time, and with the lowering of the speed of the engine and with the aid of the wings, the machine may be allowed to soar, as before described.

I have shown no particular steering means for the machine and to this extent, the controlling of the engines are used for that purpose. It has been stated that the controlling means of the engines are positioned adjacent to the seat and thus, one of the motors may be run faster than the other at any time desired, whereby when it is desired to turn the machine in one direction, the speed of one of the engines is increased, while when it is desired to turn in the opposite direction, the speed of the opposite engine is increased. Should one of the engines, by accident, become disabled, it will be seen that by merely drawing the clutches 39 and 40 into their effective positions by means of the levers 42 and 43, the sets of propellers on both ends of the machine may be run by the other engine, and should both engines become disabled, which is an extraordinary and improbable incident, the parachutes and wings may be thrown into their extended positions and it will be seen that the machine may be gently lowered to the ground without liability of accident. It will thus be seen that the machine may be under perfect control at all times.

From the foregoing, it will be seen that I have constructed an aerial vessel which is practically operative. Furthermore, it will be seen that the position of the propellers and the means for operating the same will transmit ascensional and descensional force and will cause the machine to be driven forwardly.

It will further be seen that with the provision of the pair of engines having operative connection with the sets of propellers, the machine may be readily steered thereby through the increasing or decreasing of the speed of one or the other. It will further be seen that I have provided means whereby both sets of propellers at the ends of the machine may be operated by a single engine should one of the engines become disabled. Furthermore, it will be seen that through the use of the parachutes and wings, the machine may be allowed to descend gently without possibility of accident.

It will still further be seen that the machine complete is of extremely simple con-

struction, but effective in operation and under perfect control at all times.

What I claim is:—

1. In an aeroplane of the class described, the combination with a pair of planes spaced one above the other, a plurality of propellers carried thereby and a source of power for said propellers; of a shaft extending longitudinally of the upper plane and rotatably mounted thereon, wings pivotally carried on the ends of said shaft, and means to raise and lower said wings, a portion of said means being also adapted to rotate said shaft. 70

2. In an aeroplane of the class described, the combination with a pair of planes spaced one above the other, a plurality of propellers carried thereby and a source of power for said propellers; of a shaft extending longitudinally of the upper plane and rotatably mounted thereon, wings pivotally carried on the ends of said shaft beyond the ends of said planes, a lever pivotally mounted on said shaft intermediate of its ends, and connecting means between said lever and the wings to raise and lower the latter as said lever is operated, said lever being also adapted for the rotation of said shaft. 85

3. In an aeroplane of the class described, the combination with a pair of planes spaced one above the other, a plurality of propellers carried thereby and a source of power for the propellers; of a shaft extending longitudinally of the upper plane and rotatably mounted thereon, wings pivotally carried on the ends of said shaft beyond the ends of said planes, a lever pivotally carried on said shaft intermediate of its ends and extending through an opening in the upper plane, and means connecting said wings with the lever above and below its pivotal point to raise and lower said wings, said lever being also adapted to rotate said shaft. 95

4. In an aeroplane of the class described, the combination with a pair of planes held in spaced relation with one another by means of a plurality of vertical bars, a pair of vertical shafts rotatably mounted on said planes adjacent the ends thereof and having propeller blades on the upper ends thereof, and a pair of horizontal shafts rotatably mounted between the ends of the planes, said latter shafts being provided with propeller blades at both ends thereof; of an additional pair of horizontal shafts adjacent the ends of the lower planes, connecting means between said last referred to shafts and the propeller shafts and means to independently rotate said additional horizontal shafts. 100 110 115 120 125

5. In an aeroplane of the class described, the combination with a pair of planes held in spaced relation with one another by means of a plurality of vertical bars, a pair of ver- 130

tical shafts rotatably mounted on said planes adjacent the ends thereof and having propeller blades on the upper ends thereof, and a pair of horizontal shafts rotatably mounted between the ends of the planes, said latter shafts being provided with propeller blades at both ends thereof; of an additional pair of horizontal shafts adjacent the ends of the lower plane, connecting means between said last referred to shafts and the propeller shafts, means for the independent rotation of each of said additional horizontal shafts, and additional means to rotate the vertical propeller shafts independently of the horizontal propeller shafts.

6. In an aeroplane of the class described, the combination with a pair of planes held in spaced relation with one another by means of a plurality of vertical bars, a vertical shaft and a horizontal shaft rotatably mounted at each end of the planes, the vertical shafts having propeller blades mounted

on the upper ends thereof and the horizontal shafts having propeller blades at both ends thereof; of a pair of additional horizontal shafts rotatably mounted adjacent the ends of the lower plane, connecting means between said additional horizontal shafts and the vertical and horizontal propeller shafts, a pair of motors mounted on the lower plane and having operative connection with said additional horizontal shafts to rotate the same independently of one another, means to rotate said additional shafts from the same source of power, and additional means to operate the vertical propeller shafts independently of the horizontal propeller shafts.

In testimony whereof I hereunto affix my signature in the presence of two witnesses.

JOSIAH SPARKS.
